LIQUID SPRING

BACKGROUND OF THE INVENTION

Rolled or keyed pressure vessels are in common usage in low pressure fluid systems but have never been successful in high pressure vessels. Use of crimped, levered end closures overcomes these existing deficiencies.

SUMMARY OF THE INVENTION

A crimped structural end attachment for a pressure vessel particularly suited for making low cost liquid springs, spring shocks and apparatus.

DESCRIPTION

A crimp comprising a series of radial gatherings at the end of a cylinder in which the metal is formed without substantial prestressing or stretching, holding an end cap by lever action against the edge of a relief in the cap, or using the short contact to said cap created by metal spring back to effect a levered, reinforced high pressure cylinder assembly.

This invention is related generally to low cost Liquid Springs which use molecular compression for energy storage and more particularly to a method of manufacture of all mechanical end attachments for tubular structure whereby any force up to the rupture force of the tubular structure can be obtained without employing threads, rivets or weldments.

Containing a body of liquid or gas under pressure at low cost has been nearly as difficult a problem as sealing sliding piston rods which pass through cylinders. Numerous methods of accomplishing end closures for all tubular structure are used in present day production. For higher pressures the most common method is to make cylinders with a solid end with the utilization of an enlarged threaded section at the rod end which has less stress first due to rod area and which enlargement secondly reduces the stress level at the root of the thread to stress limits which are 60% to 70% of the cylinder wall. The enlarged end is generally 120% of the area of the cylinder in which the piston reciprocates. Sometimes both ends are threaded with a loss of efficiency spacewise. This provides long life with repeated flexure as is detailed in most stress data on materials. Because of the difficulties of manufacture, more often than not, this enlargement for threads is accomplished by increasing the external dimension at the threaded end. This however reduces the efficiency of the device when compared with the volume it occupies, due to the enlarged ends, since in most instances, the cavity or clearance for the tubular structure or Liquid Spring or other hydraulic device must be sufficient to accommodate the large ends. Where said enlarged ends are formed inwardly, to provide a smooth exterior, and more efficiency spacewise the threaded section is reduced below the bore of the tube which makes it difficult with respect to flow or with cylinders to machine and finish. In the most common application of a headed piston it makes it impossible to get the cylinder head in the cylinder bore. This has restricted this construction to Liquid Springs with a small piston or spring shocks which employ an inner shock tube similar to my U.S. Pat. No. 3,256,005 FIG. 4 and FIG. 15. However, this construction is totally unsuited for hydraulic and/or pneumatic cylinders where an enlarged piston head is used which is slidable in the bore. (Such as FIG. 1 of

the subject Patent.) In addition, either the inwardly formed enlargement or the outwardly formed enlargement for said threads increases material costs since the per pound cost of tubing has a cost base 300% of bar stock, and labor direct costs increase to the point where such devices were unacceptable for the lower pressure, high volume, high production type of work. In these latter products straight thin wall tubing, end caps and threaded tie rods restraining said end caps are generally used. Liquid springs and high pressure hydraulic and pneumatic cylinders generally cost 60% more than conventional tie rod cylinders for this reason. In the case of pneumatic and hydraulic cylinders, snap rings are also sometimes employed with uniform heavier wall tubing which while less costly than threads, provide substantial holding power. Nevertheless, snap rings develop the same difficulty as the thread in that the root of the snap ring groove fails first, either by fatigue or load. In many instances using this construction, this inventor had distorted the entire end of the cylinder beyond the snap ring groove and the end had blown out. In the subject invention the effect of the snap ring without reduced wall weakness is accomplished.

Another method sometimes employed in fabricating hydraulic cylinders is that of using fusion or arc welded end caps on uniform tube structure such as automobile shock absorbers, but this is only suitable for such extremely thin walled low pressure, small cylinders and is unsuitable for high pressure devices or large diameter low pressure cylinders with heavy walls. In thin tubes or small cylinders, the weld penetration provides a structure strong enough to withstand the pressure. The exception in thick wall tubes to this process is flash butt, electron beam or friction welding where a local enlarged weld section can be joined. The wall must be 115% of the thickness of the wall joined since the weld carries an 85% rating. This process, relatively new, eliminates some of the solid cylinder drawbacks mentioned heretofore but isn't any more efficient than the threaded wall spacewise and it is costly and time consuming.

By far, the bulk of the hydraulic and pneumatic cylinder manufacture comprises a low weight, low cost tube of uniform cross section fabricated, finished, honed and polished as one large tube. In this efficient method of fabrication, the tube is then cut to individual cylinder lengths. One tube end is provided with an entrance radius to enter the seals and the entire assembly is clamped between two end caps which are held under sealing pressure against the cylinder by four or more tie bolts whose purpose is to hold the assembly together. While this latter construction is among the most prevalent in the low pressure high volume production cylinders, it is the most inefficient spacewise and also one of the most unreliable. The tie rods often stretch. The tie rods are often asymmetrically loaded. In addition, they generally employ static face seals which require even tensioning. This structure cannot be used for moderate to high pressures and is totally unsuited for Liquid Springs.

The assembly time to run down a plurality of nuts on tie rods to uniform tension is tedious, time consuming, costly and requires reasonably close torque accuracy. Servicing said cylinders requires knowledge beyond most maintenance departments.

When the above cylinders are repaired it is normally done either at the manufacturer's plant or at a central repair depot handling that manufacturer's parts. The rule of thumb is that a rebuilt and repaired cylinder will cost 60% of the original cost. Besides this cost, the fact that the cylinder is not available for continuous production and requires a heavier investment for spares, to avoid excessive down time, is detrimental. In the case of the production facilities of the automobile companies, in most instances they tear all the hydraulic cylinders out of production equipment at the time of change over of models and have them all repaired at once. Since the annual change occurs at the same time for most manufacturers, obviously, this overloads the repair facilities increasing cost further. Since the other elements of hydraulic apparatus-seals, rods, etc.-now last relatively long, the fatigue limits of cylinders, tie rods and threads are often exceeded before the second refurbishing is required. Thus the reliability of said devices after the first repair is doubtful. This results in costly breakdowns.

Even in the instances of Aerospace uses where the most costly enlarged threaded section is a must for space, weight and strength, the cost and time in repairing cylinders, especially in the event of a war on a far off shore, is exceedingly high and the logistics of shipping parts back and forth to repair bases is costly.

In addition to this, often the repairs are unsatisfactory and in most instances the military abandon the cylinder and install a new one. Consequently, in market surveys I have found a great interest even in military uses for a throw-away cylinder which could be disposed of and a new one put in place. In the mass production processes, demand is very great. The economics of the situation indicate that a throw-away cylinder of 60% the cost of the other types and, lasting the same amount of time as a repairable unit, will effect a direct overall net saving of 40% with an initial cash savings of 40% because the first installation is only 60% of the total cost. This, in turn, will reduce the initial purchase price of all types of apparatus that employ tubular structure cylinders, actuators, tubing or piping and freight is eliminated.

Because of a shortage of trained repairmen all industry and consumer goods are increasingly throw-away items, provided costs are 60% of serviceable items. My process adds hydraulic cylinders and Liquid Springs to this class of merchandise. Additionally, in case of Aerospace and products of high stress, it has always been considered that any method of fabrication other than threads or welding, could not be fabricated in the high strength materials. Therefore, the ability to accomplish a low cost fabrication method in high strength materials has heretofore been deemed beyond the capability of technology and the state of the art. With my method disclosed herein, any material can be utilized as tubular structure and pressures retained therein. I have actually crimped 350,000 p.s.i. yield steel and cycled said unit over 1,000,000 cycles without failure. This is evidence of the merit of this invention.

Formerly, it was essential to have an enlargement or a thickened section of a cylinder for threads to restrict pressures up to 40,000 p.s.i. For a period exceeding 10 years this inventor has attempted to mechanically hold an end cap of a high pressure Liquid Spring without the necessity of using threads or tie rods. Most experiments to date have centered around a grooved end cap (FIG.

4, U.S. Pat. No. 3,256,006) into which the cylinder is rolled, hydrostatically formed or otherwise displaced to replace threads or snap ring in restraining such end cap movement. These previous methods have all been dismal failures as while the liquid could be restrained by such methods, fatigue failures occurred due to the overstressed condition where said material was rolled over an end cap or rolled into a groove. None of these devices ever exceeded 50,000 cycles in life, whereas the subject of this invention has resulted in life in the millions of cycles exceeding all other construction including threads and, in fact, have yet to fail. In most instances the cylinder wall fails elsewhere without failure at the end cap closure.

15 The methods of cap retention noted above has resulted in tests in the holding of pressures to 40,000 p.s.i. with walls that were only capable of holding 20,000 p.s.i. without bulging. This was accomplished by holding the cylindrical member in a closed cavity and just permitting the cap and crimped end to be exposed so that all pressure was imposed on the end cap at 40,000 p.s.i. The end cap had still not failed at 40,000 p.s.i. with a cylinder wall capable of yielding at 20,000 p.s.i.

20 25 While this system was considered and designed primarily for low cost Liquid Springs, the method has been found adaptable to Liquid Springs and hydraulic apparatus for high performance aircraft. It provides a tremendous cost saving in that all hydraulic apparatus is now cheap enough to be thrown away and not serviced as is customary now.

30 Such an assembly method can be used in tubular furniture, golf club attachments, tennis racquets and all tubular attachment requirements and is not limited to hydraulic apparatus although it is particularly well suited where pressure is unidirectional as it is in containing pressure in a cylinder. It will function with square or other cross sections.

35 40 Since this process is primarily designed for my specialty, molecular compressibility devices, (Liquid Springs), it is intended to lower the cost of such devices so that they will replace low cost coil springs in all stamping dies. Heretofore my liquid die springs have been limited to special situations. For instance: referring to one actual application, the force required to strip demanded a five station progressive die but Liquid Springs (forces generally 20 times coil spring forces) permitted a one die application, providing savings in die costs.

45 50 To increase the market further, higher operating velocities are desired. Seal friction is the limiting factor. I have determined that pistons employing the porosity of cast iron or stainless steel cut friction to half that for stainless steel pistons of bar stock thus doubling allowable cycle speeds.

55 60 Theoretical calculations show temperatures of 2100°F. on the leading edge of my seal at 100 cycles per minute 1 inch stroke with a stainless piston made from bar stock. This is 3 times the temperature at which silicones and teflon vaporize. Actual tests with a high strength hollow stainless piston, boiled water in 100 cycles and melted nylon powder (550°F.) under continuous cycling at 100 cycles per minute. Since cast materials do not conduct heat as well as bar stock, part of the gain with 50% of the friction is lost as heat dissipation is reduced. I seek in this application to increase this dissipation.

It was further determined that heavy wall cylinders tended to contain heat. Design studies proved that dropping pressures from 20,000 p.s.i. to 10,000 p.s.i. and reducing wall thicknesses provided a spring having 85% of the energy capabilities since the large liquid volume replacing the steel gained energy and the heat dissipation out the wall was enhanced. Crimping then became easier and a low cost commercial high speed liquid spring was provided.

The primary object of this invention is to provide a joining method for tubular structure which equals or exceeds the strength of the parent uniform wall tube, at the joint so formed.

The second primary object of this invention is to provide a low cost throw-away Liquid Spring, hydraulic or pneumatic cylinder.

A third primary object of this invention is to provide an efficient cylinder without end enlargements or highly stressed section.

Another primary object of this invention is to provide a method of forming which is capable of converting tubular sections of uniform cross sections to reinforced end wall closures.

The related object to this invention is to provide a method of forming which is capable of containing an end closure in tubular sections of uniform cross sections of any shape.

Yet another object is to provide a low cost method of assembly for throw away hydraulic apparatus wherein the fatigue life of the cylinder exceeds the seal life so that no downtime is created before the cylinder is worn out.

A related object is to force the replacement of structural elements of hydraulic apparatus prior to fatigue failure.

A Liquid Spring object is the reduction of friction in a high speed Liquid Spring.

A companion object is the dissipation of heat in a high speed Liquid Spring.

A further object is the lowering of Liquid Spring pressures and cylinder wall thickness wherein crimping can be accomplished.

A related object is the reduction in wall thickness wherein high internal liquid temperatures can be more readily dissipated.

A companion object is to pump liquids adjacent to the high temperature seal lip area to reduce and dissipate high temperatures therein.

Another primary object of this invention is to make closed cylinders for pressure use without threads, weldments, or tie rods.

A companion object is the reinforcing of end walls of tubular devices without heat wherein they contain an end closure.

A related object is the reinforcing of end walls of tubular devices without stress risers.

Another object is the reinforcing of end walls of tubular devices without stretching or prestressing the material.

The further related object of this invention is to provide a method of fabrication which can employ the highest strength materials in its low cost method of fabrication.

A companion object is to provide a method of fabrication which avoids over stressing the retention means.

Another related object of this invention is to provide a method for the fabrication for precision hydraulic

cylinders which is so economical the cylinder can be thrown away when repairs are necessary.

Still another object of this invention is to provide a method of fabricating a cylinder from uniform wall cylinders for ultra high pressure devices such as Liquid Springs and Liquid Spring Shocks.

A secondary object of this invention is to provide a method whereby Liquid Springs can be fabricated in mass production using unskilled help.

10 Yet another related object of this invention is to provide a liquid spring assembly wherein the preload and end load can be automatically determined in the assembly processes.

15 Yet another object of this invention is to reduce costs and provide a throw-away cylinder whereby freight costs one way are saved.

20 Yet a further object of this invention is to eliminate all downtime except exchange time for hydraulic apparatus.

25 Another liquid spring shock object of this invention is to provide an energy responsive metering means.

A related object of this invention is to provide damping response proportional to mass and/or velocity in a liquid spring shock.

30 Still another object of this invention is to eliminate all downtime due to repairs.

35 Yet another object of this invention is to provide a method of assembling all hydraulic or pneumatic apparatus by crimping.

A related object is to provide simple percussion or squeeze assembly procedure for pressure apparatus.

A further object is to provide hydraulic apparatus fabricated and assembled by press working.

35 Yet another object of this invention is to provide a low cost method of assembly for automobile shock absorbers.

These and other related objects will be apparent from the following drawings and specifications.

40 FIG. 1 is a side elevation in section of a low cost Liquid Spring employing the method of fabrication by crimping the cylinder for holding the high pressure, end closure and seal therein.

45 FIG. 2 is a similar view of a vehicle spring shock, using an inner tapered shock tube and a uniform tube for the cylinder and employing solid end caps with an eye attachment for an automotive rubber isolation bushing and a seal and end cap in which cap retention is accomplished using metal spring back and the flare out for seal entrance.

50 FIG. 3 is an enlarged fragmentary sectional view of the end closure of FIG. 1 in enlarged detail which illustrates the restraining forces for holding the end closures.

55 FIG. 4 is a typical end view after crimping of FIG. 1 or FIG. 2, showing how the cylinder metal was reformed, not stretched, to restrain the cap.

FIG. 5 is a view of an alternate stiffened wall before forming which is a means of lowering the wall yield or notch effect, for highest loads and life particularly in soft material.

FIG. 6 is a view after forming the end closure of FIG. 5 showing that the cylinder is still efficient spacewise.

60 FIG. 7 details a low cost seal for use with the Liquid Spring of FIG. 1 with preload end stop shock absorber included in the seal and a heat dissipating hollow piston.

FIG. 8 is an alternate method of construction in which the end flare and spring back of metal accomplishes the desired seal entrance and end closure purposes and a separate preload or end stop and shock absorber is employed with my older seal and a hollow piston for heat dissipation.

FIG. 9 is a method of fabrication employing a combined plastic seal-end closure and preload shock absorber with a plastic cylinder and using a metal ring for the distribution of forces and retention of the end cap in the plastic cylinder.

FIG. 10 is a cross section of the preferred die assemblage which does the end cap retention by cylinder crimping while simultaneously holding the proper preload on the liquid spring piston end cap simultaneous with the crimping.

FIG. 11 is a longitudinal section of an alternate low cost die for low volume production.

FIG. 12 is a section of this die, taken as noted on FIG. 11, and is typical of longitudinal crimping dies.

FIG. 13 is an alternate method of fabrication using a four slide press, crimping by side action against the cylinder.

FIG. 14 is a view of a double acting hydraulic or pneumatic cylinder employing the crimped end faces and standard tubing which is fabricated in the same manner and using cast plastic end faces and cylinder heads.

FIG. 15 is a hydraulic or pneumatic cylinder with stamped end caps and stamped piston heads and using crimping as the end retention means.

FIG. 16 is a pressure vessel constructed of uniform tube sections and with the stamped end caps of FIG. 15 held by crimping.

FIG. 17 is a sectional view of a typical crimped end fitting assembly of uniform pressure tubing used to carry fluids.

In FIG. 1, I show a longitudinal section of a Liquid Spring 20, or other high pressure piston type device which utilizes the novel high production crimping method I have developed for the retention of high pressure in an efficient cylinder without weldment, threads, tie rods, snap rings or other high cost assemblies. In FIG. 1 is shown a liquid spring 20, having a cylinder 21, with an integral end closure 22, and an upstanding wall of uniform cross section 23, which is essentially straight and uniform in every respect. This is essentially a closed cylinder made by cold extrusion or deep drawing process in which with crimping reduces costs of liquid springs, energy-wise below coil springs. A liquid 24, is enclosed with a seal member 25, and a cap 26. Said seal 25, being restrained against cold extrusion by the guide ring 27. Guide ring 27, acting as a wiper and anti-extrusion member for piston 30. Piston 30 has the head 31, as shown hereinafter in FIG. 7 bearing against seal 25 for purposes of restraining it therewith. With the exception of crimping it is similar to my low cost Spring U.S. Pat. No. 3,256,005. Referring now to FIG. 4, an end view of the configuration is shown which illustrates how the cylindrical wall 23, is displaced by forming rather than stretching or embossing. Said wall 23, being displaced at 23b has essentially four small semi circles having a bent radius equal to a minimum of 1 1/4 times the thickness of the upstanding wall 23. This gathering, or radial displacement of the metal reduces the diameter of cylinder 23 at the end closure and causes an inwardly formed tapered shoulder 23b, to restrain cap

26, against axial movement thus effectively restraining the high pressure fluid 24, through seal 25, cap 26, and surface 23b and shoulder 26b of cap 26. It should be noted that if this end wall formed configuration is again made circumferential after having thus been formed, it would have identical circumferential dimensions to that which it had been before forming. This is a key ingredient of the success of this method of retaining high pressures without wall failure at the stress point where forming begins and shoulder 26b engages wall 23b.

Referring to FIG. 1 and 3, to avoid critical variations in spring back in metals, I prefer that cap 26, has a recess 26a, so designed to provide a shoulder 26b, which is the fulcrum point of the bending of the wall 23. This control eliminating the effect of spring back is an important ingredient of this invention and a main reason for the capabilities of this design to hold extreme pressures without fatigue failure. This is rather obscure unless the interrelations of the shoulder 26b, and disclosed forming methods are carefully considered. A seal entrance lead angle 23d, is machined from the lip of cylinder 23, this permits 23a to be tapered in proportion to thickness if it is desired. In thick walled cylinders, such as those Liquid springs under very high pressure this taper can be enhanced to provide a much thinner wall at the opening or tighter crimp so that the die formed bend radius can get progressively smaller in accordance with the minimum 1 1/2 thickness. We thus can form the highest pressure liquid springs in accordance with these principles. This is an important feature of this invention. From experiments I have found that about 35° to 45° inclination of the wall is best. As noted at 26b intersection of wall 23b approximately a 60° keying of wall 23b is accomplished. This is essentially the incline of a holding thread and seems to work best just as the same angle works best in a thread. The forces seem to be resolved without failure, over millions of cycles, when this is accomplished this way. Actually, it has always been considered in design that only one thread holds in a threaded joint so the success of this crimping method with its thread-like holding can be readily understood. The obscure reasons why this retention means holds such high pressure is further made apparent in FIG. 3.

If one observes the longitudinal line of force from the 60° face formed by the edge 26b in inclined wall 23b, it will be seen that it goes through the center of mass of the crimped stiffening bead formed by radius 23a. This 30° incline with its resulting direction of force from the 60° engagement through the stiffening, plays a part in the long fatigue life of this formed end closure. The angle can vary, but best results appear dictated by this force direction noted.

In FIG. 3 surface 23b, is bent about its centroid 28, placing fibers 28b, in compression and increasing the thickness locally. Fibers 28a, are placed in tension. It should be noted that the stress gradient across the wall of a cylindrical pressure vessel is high on the inner surface and low on the outer surface so that this bend makes the wall resistance greater because it prestresses the wall 23b, against the force 33, working to fail wall 23b. This end closure 23a-23b is fabricated by bending rather than stretching, as in roll forming, so its stress is low. This alone is not enough to hold cap 26, as it is necessary to provide the effect of a thickened end section similar to threads. In effect this thickened gathered section provides a lever action to hold the cap 26. To

accomplish this, a small lever couple 29—29, is formed between centroid 28, and shoulder 26b, acting to cause the opening of formed wall 23a—23b from force 33. The entire mass of the formed stiffening end 23a, 23b, forms a large resisting couple 30—30, resisting end opening. This is the equivalent of many threads in the old high stress cylinder construction. In effect then the thickened-stiffened section 23b, and rigidized webs 23a, act as the old thickened ends which were threaded but they are formed from uniform tubing. Further, it is well known that as you approach the central axis of a cylinder, the stress on a given wall thickness is lowered. Thus forming the cylinder inward automatically lowers its stress if the wall thickness is not reduced. Please note that roll stretch forming prestresses the wall causing it to fail in fatigue, as I have demonstrated many times. Forming without creating local stress patterns and without stretching as done here, eliminates the stress pattern that cold works and prestresses the material to early failure.

Summary:

1. The inner fibers are in compression and pre-stressed against movement.
2. The couple attempting to open the end closure is extremely small magnitude and the couple restraining has large magnitude.
3. This couple is of a predetermined magnitude, when the fulcrum point about which the cap is restrained is predetermined by a relief on the cap.
4. Walls of uniform thickness moved to a lesser diameter automatically lower stress levels.
5. The line of force from the end closure engagement goes through the center of mass of the stiffening ribs.

In FIGS. 5 and 6, I show a detail enlargement of this construction, but here when using some soft alloys I have increased the metal wall at 23p. 23p is enlarged very slightly on its exterior so that the depth of the impression of the cap in this soft metal would not exceed the depth equal to the normal thickness of the wall 23. This would prevent fatigue failures in soft material such as aluminum and brass and provide for a long life. Note that the cylinder after forming has no interior enlargement permitting a piston head entry, but it has no exterior enlargement after forming so it will still fit in an efficient space envelope even though section 23p is enlarged.

In FIG. 2, I illustrate the manufacture of a Liquid Spring shock 40, which has a thin tubing wall 43, an end cap 42, and a seal retainer cap 46, construction suitable for existing vehicle shock absorbers. The advantage of this device is that of using tubing with two end caps to provide a cylinder assembly and is the procedure most widely used in all hydraulic apparatus with the exception that said thin wall tube 43, is generally restrained between two end caps held by external tie rods or at times welded. The configuration of the crimped end cap 43a—43b, is identical to that formerly employed except the spring back of the metal of tube 43, is utilized to provide a similar leverage principle of retention to that of FIG. 1. The differences between the two methods of construction, will be detailed hereinafter, since the purpose of this view is to illustrate that tubing can be used and that crimping can be accomplished on either end and that only metal spring back may be utilized instead of an external recess 26a FIG. 1, 3, on the cap. This construction has an inner tapered

shock tube 47, bearing 47a, on the seal gland 45. A piston head 40a, of piston 41, slides in the shock tube 47, to provide the dual spring rate of my copending patent application Ser. No. 619,531. At present, automobile shocks are seam welded at each end, but that construction uses mild steel for costs. Here tube 43, is alloy steel but the end caps can be mild steel. These dissimilar parts could not be easily welded but can be made as shown at low automotive costs. Piston head 40a, has a slight uniform clearance 47c, to the inner bore 47a, of tube 47, and a liquid clearance hole 47e. Taper 47f, provides for progressively greater deflection of tube 47, as pressure increases in liquid 44, on impact, closing off clearance 47c, and thus increasing shock force. Hole 47f as it is closed off increases liquid restriction in accordance with the declining velocity of piston 41 after impact.

Now I have determined that spring back can be utilized to provide the same couple while it is not as predetermined as the cap with the relief, it is effective particularly where pressures are of a lower nature. In FIG. 8, I illustrate the principles used in FIG. 2 wherein the spring back of the metal provides a short couple for retention of the cap X which is restrained by the large couple T. This will only work where the metal being deformed is sufficiently elastic at high stress to provide spring back or yield. With extremely soft nonelastic material without spring back, the cap will blow out of the cylinder with ease as we have determined in our tests. In this instance or with very high liquid spring pressures the relief 26a of FIG. 7 is a must.

Referring now to FIG. 7, an enlarged fragmentary section of the construction is illustrated. The novel seal 25, differs from my U.S. Pat. No. 3,256,005 in that a fluid energizing groove 25a, is made with a thin trepanning tool in one operation. In addition, Lip 25b, is shorter to avoid head 31 of piston 30. Seal lip 25c, is relatively very thick and extends further into the liquid 24, and has an angle 25d, which is engaged by a similar 45° face 31b of piston head 31, producing a force component 35, when the piston 30 bottoms in shock, or to hold a preload condition. With teflon seals which tend to cold flow this carries the force to the external wall 23, and directs it generally to fulcrum point 26b, without changing the length of the assembly.

With teflon seal 25, piston 30 is preferably of a semiporous cast iron or stainless steel material to retain teflon in its porosity and cast structure, to provide better sealing and lower friction. Bore 30e, acts to carry liquid 24, to the exposed end of piston 30, conducting heat and promoting "leak free" life.

Piston Head 31, has a plurality of Borda Mouthpiece bores 32, having a 50% flow coefficient at 32a, and a 98% coefficient at 32c. This serves to reduce shock on seal 25 and acts as a pump to cool the Liquid Spring, along with flow through holes 30f.

The guide, anti-extrusion and wiper member 27, has an enlarged section 27b, and wiper lip 27a, extending beyond cap 26.

FIG. 8 also illustrates how cylinder end 23a, of cylinder 23, was first flared out at 23f to provide a seal entrance and then crimped in after the seal 55, is inserted. It should be noted that this provides a land 23c, after spring back that functions the same as the relief 26a, in the cap 26, of FIG. 1. Flare 23f can be extended back to point 23c if desired to provide the entire relief. Seal 55, is similar to that in my U.S. Pat. No. 3,256,005, but

a shock member 56, of plastic fits between lips 55b and 55c, and keeps them in engagement under high speed operations. A bore 56a, adds liquid dampening on shock impact of piston 70. A guide and anti-extrusion element 57, is also used. Piston head 70 impinges on shock isolation member 56 and prevents seal lip surges from sudden stops as occurred with the metal retainer of U.S. Pat. No. 3,256,005. The thickened lip 25c of seal 25 FIG. 7, functions similarly but is one piece. Both seal 25 of FIG. 7 and seal 55 of FIG. 8 have heavy interference to their respective cylinder walls. This interference provides a tight elastic fit in the cylinder holding fixture of FIGS. 10, 11, 12, 13, which will be discussed hereinafter, assuring a smooth crimp. In general, all crimp operations need end wall stiffening at the crimp as it takes place, and the end wall closure and seal should provide this rigidity.

In FIG. 8 piston 70 is hollowed 70a at the other end to that of FIG. 7, similar to my experiments noted hereinbefore. Actually air flowing in or out on cycling acts to cool the seal. The hollow 70a in piston 70 can be filled with temperature conducting liquids and sealed and it is so contemplated here.

FIG. 9 illustrates a fragment of cylinder 60 and seal assembly, end cap 65, including a part 66, on an extension thereof. Both cylinder wall 63 and cap seal 65, are plastic and crimp 63a, and 63b, is done hot. A metal ring 70, locks at 63b, to hold plastic seal end cap 65, in cylinder 63. This inventor has filed Patents under co-pending patent applications Ser. No. 619,531 filed Feb. 27, 1967 in which liquid springs use a nylon cylinder such as cylinder 60, having a nylon wall 53, which is utilized because of the elasticity of the wall providing up to 62% of the spring energy as has been discussed in my copending applications. In this instance, a seal cap end 65, is employed to restrain the seal, being of a similar plastic, such as Delrin-AF which employs Teflon fibers as reinforcement for seal lubrication purposes with the high strength of Delrin. However, except for low pressures, it is believed that the corner method of retention noted in FIG. 3 would not function with plastics. In this instance, I thus insert the metal like ring 70, which acts to provide the necessary bite or engagement with the wall 63, while simultaneously providing the simplicity of molded plastic parts.

FIG. 10 is a view of a die assemblage 80, having a female die 81, which has a pluralities of cavities 83 for forming the upstanding cylinder portion 23, of the Liquid Spring 20, as the punch 81, is actuated axially toward the Liquid Spring cylinder portion 23. In each of the four cavities 83, shown in the punch 81, in FIG. 10, and in a related die section (FIG. 12), I gather and fold the metal to provide the upstanding columns 23a, of cylinder wall 23. In essence, piston 30, seal 25, and cap 26, is held against liquid pressure 24 in the Liquid Spring by the internal holding fixture 85. It is intended that fixture 85 read pressure and length of spring 20 so that the proper preload and overall length of the spring can be determined prior to crimping. While the liquid volume is measured carefully variations exceeding the allowable tolerances can be read by force on the holding fixture 85 and crimping stopped if the spring is too low or high. Automatic procedures and rejection can also be incorporated. The cylinder assembly 20, is held in the cavity 91, of a restraining fixture 90, so that the crimping forces do not cause the corrugation or failure of the wall 23, as crimping takes place. The cavity 91,

of the restraining fixture 90, will hold said cylinder even though there is no internal pressure in the cylinder. It should be noted also that seal 25, generally of teflon, has a substantial interference to cylinder wall 21. Subsequently, this diminishes as the teflon cold flows but at the time of the crimping operation this interference or response resistance makes possible the crimping of the seal in place without axial movement or wall corrugation. A simpler die 100, shown on FIG. 11 and FIG. 12 can also be used without member 85 of FIG. 10 by cooling the Liquid Spring 20, shrinking the liquid to reduce its resistance, and then crimping the cylinder with die 100. Plastic sleeve 101, protects the piston 30.

In the production of some products, say where a piston has a large head, or a tube fitting, it may be required to cause said crimping by a lateral motion instead of a longitudinal motion. This then would permit the use of headed devices and to accomplish the restraint shown without the necessity for axial movement. This would also eliminate the necessity for a restraining fixture 90, since the application of the metal distorting forces is at right angles to the cylinder or tube. We therefore show a Liquid Spring assembly 20, and a four-sided punch machine 110, in which a plurality of punches 111 move toward the cylinder 20, crimping the cylinder 20, at 26, while simultaneously causing the crimping of the cylinder and the holding of the pressure.

It is also contemplated that a spring roller assemblage in which the rollers move vertically from the seal area to the open end of the cylinder could also accomplish the crimping of the cylinder. This method is not shown but it is intended that any type of metal distorting tooling providing the crimps 23a, 23b, of a cylinder 20, is acceptable for this purpose.

It should be further pointed out that in the use of plastic cylinders said punching tools or rollers would be heated so that the thermoplastic could be caused to distort the otherwise elastic plastic and formally accomplish the permanent yield of resilient plastic of the shape desired. It is further contemplated that, in the event alloys having critical cold working properties are utilized that induction heating or heating of just the punches or crimped end over a time interval might eliminate the cold working stresses for those brittle alloys having cold working fatigue problems. I have successfully crimped 350,000 yield maraging steel and obtained 1,000,000 pulsations or reversals without fatigue failure. The Liquid Spring was cycled so that its internal pressure varied between 2,000 and 20,000 p.s.i. each of its 1,000,000 cycles.

I have described my invention in connection with the product for which it was designed, that is ultra high pressure hydraulics or Liquid Springs, I will now describe in detail how said materials can be also utilized in low pressure applications such as pneumatics and hydraulics. While primarily developed for high pressure applications and for which no method of mechanical crimping has ever been found satisfactory, it is obvious that these principles when applied to low pressure hydraulic and pneumatic cylinders accomplishes a corresponding reduction in cost. Thus, cost reduction lowers the cost of hydraulic and pneumatic cylinders to 60% of its former cost which is the cost for repairing an existing hydraulic cylinder. It is thus apparent that throw-

away hydraulic cylinders are now possible with a reduction of 40% in the cost of said equipment.

In FIG. 14, I show a low cost hydraulic cylinder assembly 120, having a tubing cylindrical member 121, which is a piece of homogeneous tubing extruded or rolled and honed to the standard lengths for that tubing, that is 20 feet or more and cut to length, say 1 foot in length, as it is used in this FIG. 14. FIG. 14 illustrates, in general, a low pressure pneumatic or hydraulic cylinder having an end cap 126, from which a piston rod 130, extends through a seal 125, said piston rod 130, having an enlarged head 131, thereon and a seal 132, thereon for actuating as in a customary pneumatic or hydraulic cylinder.

It should be noted that seal 125 is of teflon having a gaseous transition at 700°F. so that a probable cast material such as urethane, bakelite, et cetera, could be cast around seal 125 since its pour temperature is less than teflon gaseous transition. This thus provides a cast end cap with a precision seal.

Actually, since the total energy capacity of plastics is used in the process of ablation used in space re-entry vehicles to prevent destructive heat from damaging the occupants, a reverse process can be used here. Cast metal can actually be cast around a cold teflon seal, since metals having lower temperature melting would solidify and cool prior to the vaporizing of much teflon. The teflon could actually employ sacrificial upstanding ribs which, while partially or completely vaporizing would lock in. After said attachment cold flow of the teflon could be made to refill the voids where vaporizing of the sacrificial sections had taken place. Piston rod 130, has an enlargement 131, forged thereon about which the plastic piston head 131a, is cast. Ring 132 is also fixtured and cast and is a homogeneous teflon ring acting as the piston ring for said cylinder. Cap 126, which is also of cast plastic or metal construction, has a metallic ring 126a, cast integral and a seal groove 126b, which is cast and subsequently fitted with an elastomeric seal 126c. Threads 126d, are likewise cast as is passage 126e. Ring 126a, is fixtured and cast therein also. We thus have a cylinder end closure, completely cast in a die and subsequently not machined to provide a pneumatic cylinder end 126, of the type illustrated. End cap 140, at the other extremity, has a metallic ring 126a, cast therein, a seal groove 126b, cast therein and an elastomeric seal 126c, inserted therein. A threaded porthole 141, is cast integral as is the air port 142. We thus have an air or hydraulic cylinder comprising simple homogeneous tubing and employing two die cast or plastic cast cylinder ends and a piston including a die cast or precision cast piston head. These are all low cost components. It should be obvious that the ends of this cylinder can be crimped as shown by a double ended crimping operation which is done simultaneously in a press or can be crimped one end at a time by either a punch and die or a four-sided punch. It should be noted also that on large diameters such as shown here, any number of vertical stiffeners can be formed by a punch having the appropriate number of cavities to provide the stiffening the structure indicated in accordance with my teaching that the metal is bent not stretched.

FIG. 15 shows an alternate low cost air or hydraulic cylinder 150, with tube 151, which employs metal stamped end fittings 152, and 156, and stamped piston heads 161. Cylinder 150 is crimped in the fashion

shown to provide a low cost cylinder assembly. End cap 156, has an outer stamping 156b, which retains piston seal 155, and an inner stamping 156c, nested therein spot welded at 152g and providing therebetween a cavity 156d, for elastomeric seal 156f. The nested members of 156, are threaded at 156e, to hold pipe 170. End cap 152, has similar nested stampings 152b and 152c. Stamped boss 152g, has a thread 152e, which receives a pipe 180. Seal groove 152d, has a seal 152f therein. This is a simple low cost device. Prior to crimping, cylinder 150, is rolled at 158 and 159 to hold end caps 156 and 152 in place. We have thus illustrated in some detail our method of cylinder fabrication for all precision hydraulics and pneumatics, even though said machines and processes were first developed for high pressure Liquid Springs.

FIG. 16 illustrates a simple pressure reservoir 160, with tube 151, and two end caps 152, using these principles. A simple spacer tube 161 holds the end caps 152 in spaced relation while crimping takes place. Tube 161 can be high wear resistant in a soft tube 151.

FIG. 17 shows a tube assembly 170, using tube 171, and an end fitting 180, having a threaded attachment 181, a bore 190, and a reduced neck 182, an enlarged head 185, having a seal 183 in a groove 184. Crimp 193 holds the assembly together.

Having thus described by invention, I claim:

1. In a shock absorber having a housing, a piston means slidably disposed within said housing, seal means for said housing and piston means and end closure means associated with said piston, housing and seal means, the improvement comprising means for restraining longitudinal movement between said housing and said end closure means including a formed crimped section acting as a reinforced structure for said housing and a reduced section on said end closure means wherein the reinforced structure acts as a lever against the reduced section to prevent relative longitudinal movement of said housing and closure means.

2. The shock absorber of claim 1 wherein said reduced section on said end closure means is conical and wherein the reinforced structure acts as a lever against the reduced section to prevent relative longitudinal movement between said housing and closure means.

3. The shock absorber of claim 1 wherein said reduced section on said end closure is a stepped reduced section wherein the reinforced structure acts as a lever against the step in said reduced section to prevent relative longitudinal movement between said housing and closure means.

4. The shock absorber of claim 1 wherein said conical section has a sharp engagement edge formed thereon wherein the reinforced structure acts as a lever against the sharp engagement edge formed in said reduced section to prevent relative longitudinal movement.

5. The shock absorber of claim 1 wherein said formed crimped section for said housing is inclined between about 35° and 45° relative to the longitudinal walls of said housing and wherein said reduced section on said end closure means has a recess formed therein producing a sharp edge wherein the reinforced structure acts as a lever against the edge of the recess formed in said reduced section to prevent relative longitudinal movement.

6. The shock absorber of claim 1 wherein said formed crimped section has a bent radius about 1 1/2

15

times the thickness of the longitudinal walls for said housing and wherein said reduced section on said end closure means has a recess formed therein producing a radial thread profile wherein the reinforced structure acts as a lever against the radial thread profile formed in the reduced section to prevent longitudinal movement.

7. The shock absorber of claim 1 wherein said reduced section has a recess formed therein producing a radial thread profile having a resulting line of force directed to the reinforced structure wherein the reinforced structure acts as a lever against radial thread profile formed in the reduced section to prevent relative longitudinal movement.

8. The shock absorber of claim 1 wherein said re- 15

16

duced section is provided with a sharp edge thereon shaped so as to substantially direct a line of force through said reinforced structure wherein the reinforced structure acts as a lever against the sharp edge 5 of the reduced section to prevent relative longitudinal movement.

9. The shock absorber of claim 1 wherein said reduced section on said end closure provides a profile substantially like a screw thread and is arranged to provide a line of force through said reinforced structure wherein the reinforced structure acts as a lever against the screw threadlike profile of said reduced section to prevent relative longitudinal movement.
